UNITED STATES PATENT OFFICE.

FRANK E. WATTS AND DONALD T. HASTINGS, OF DETROIT, MICHIGAN, ASSIGNEES, BY
MESNE ASSIGNMENTS, TO HUPP MOTOR CAR CORPORATION, OF RICHMOND, VIR-
GINIA, A CORPORATION OF VIRGINIA.

LUBRICATING SYSTEM.

1,183,145.

Specification of Letters Patent.

Patented May 16, 1916.

Application filed December 22, 1914. Serial No. 878,578.

To all whom it may concern:

Be it known that we, FRANK E. WATTS and DONALD T. HASTINGS, citizens of the United States of America, residing at Detroit, in the county of Wayne and State of Michigan, have invented certain new and useful Improvements in Lubricating Systems, of which the following is a specification, reference being had therein to the accompanying drawings.

The invention relates to lubricating systems for engines, and has among the objects thereof to provide a simple and efficient system for lubricating various parts of the engine, and further, to reduce the number of parts required to effect a proper distribution of the lubricant.

Other objects of the invention will more fully hereinafter appear.

20 The invention resides in the peculiar construction, arrangement and combination of parts as hereinafter set forth and particularly pointed out in the claims.

In the drawings,—Figure 1 is a top plan view of a crank case having the improvement applied thereto; Fig. 2 is a fragmentary sectional side elevation of an engine casting embodying the invention; Fig. 3 is an end elevation; Fig. 4 is a section on the line 30 4—4 of Fig. 1; and Figs. 5, 6 and 7 illustrate certain details of construction.

A designates the crank case, B the crank shaft bearings and C the pan or bottom of the crank case. The crank shaft bearings in 35 the construction illustrated are formed in partitions or divisional walls D in the crank case, three of such partitions being shown in the construction illustrated. Arranged in the partitions D are bearings E for the cam 40 shaft, and in order to simplify the lubricating system, a construction is provided in which the bearings for the cam shaft receive their supply of lubricant from that fed to the crank shaft bearings.

45 Referring more in detail to the one embodiment of the invention shown in the drawings, F is a tube extending longitudinally of the crank case, and cast in the partitions D, and G are passages in the partitions establishing communication between the tube and the crank shaft bearings. Each partition is provided with a second passage H extending between the crank shaft bearing and the bearing E for the cam shaft,

The bearings for the crank shaft include 55 bushings I which are so constructed as to allow a portion of the lubricant fed through the passage G to pass to the interior of the bushing and to establish communication between the passages G and H, so that a portion of the lubricant fed to the crank shaft bearing will also pass to the bearing on the cam shaft. In the particular structure shown, each of the crank shaft bearings is of the split type, one half of the bearing being formed in the lower edge of the partition while the other half is formed in a cap a that is secured to the partition by screws J. The bushing I is also formed in two sections, the upper segment K having apertures L and M extending therethrough which register with the ends of the passages H and G. On the inner face of the bushing sections are channels N and O extending completely around the bushing and connecting each of the apertures L and M with the channels N and O are channels P and Q. Thus the lubricant from the passage G will discharge through the aperture M and onto that portion of the crank shaft journaled in 80 the bearing, and a portion of the lubricant will also pass from the aperture M by way of the channels N, O, P, and Q to the aperture R, and from the latter to the conduit H. The lubricant supplied to the conduit 85 F is under sufficient pressure to cause the lubricant to flow up the passage H to the cam shaft bearing.

In the structure shown, the tube or conduit F is connected through the medium of 90 a passage S formed in a boss T through which the tube extends, with a chamber R. U is a conduit leading from the chamber R to a pocket V on the inner face of the fly-wheel housing W. This pocket is shown as 95 of tapering or wedge-shape form, the large end being substantially the full width of the periphery of the fly-wheel X and positioned in close proximity thereto. A sufficient quantity of lubricant is maintained in the 100 fly-wheel housing so that the lower portion of the fly-wheel is immersed therein. By this arrangement when the fly-wheel is rotated at the usual rate of speed, lubricant will be carried up into the pocket V and 105 from the latter into the conduit U. The fly-wheel in effect forms a pump for forcing the liquid through the conduit U to the

chamber R and acts to place the lubricant under sufficient pressure to cause the lubricant to readily flow through the several conduits and channels.

- 5 At the end of the crank case opposite the fly-wheel housing is a housing A' within which are arranged the chains B' and C' for driving the cam shaft, magneto and other accessories. These chains are preferably 10 lubricated through the medium of the conduit F. In the structure shown in Fig. 3 the conduit F is provided at the end thereof with a branch D' arranged to discharge upon the inner face of the chain C' and 15 also with a branch E' positioned to discharge upon the inner face of the chain B'. In the construction shown in Fig. 2 the end of the tube F that projects within the housing A' is provided with a small aperture F' 20 which allows a quantity of oil to discharge from the tube F into the housing A'. Since the lubricant in the conduit F is under pressure, the discharge from the conduit F' will strike against the inner face G' of the 25 end of the housing A' with sufficient force to effect a splattering of the lubricant, thereby in effect lubricating the chains C' and B' by a splash system.

Leading from the chamber R is a conduit 30 H' that communicates with a bore or passage I' in the casing wall J'. The inner end of the bore I' opens into a chamber K' within which are arranged valve stems L', the latter being operated in the usual 35 manner from the cam shaft M'. The chamber K' is oil tight and designed to hold a sufficient quantity of lubricant to properly lubricate the joint between the valve stems L' and the valve-operating rods N'. The 40 height of the lubricant within the chamber K' is regulated by means of a pipe or conduit O' which has the upper end extending the desired distance above the bottom of the chamber L'. Oil discharging from the conduit O' returns to the crank case, as will be 45 readily understood upon reference to Fig. 5.

In use, during the rotation of the fly-wheel, oil will be fed from the fly-wheel housing by way of the conduit U to the 50 chamber R. A portion of the lubricant will pass from the latter through the passage S to the conduit F and will be distributed to the bearings through the medium of the passage G. A portion of the oil fed to the 55 bearings will pass into the conduit H and from the latter to the cam shaft bearing E. Lubricant will also discharge from the chamber R through the pipe H' and bore I' into the chamber K'. Lubricant will 60 collect in this latter chamber until it reaches the height of the conduit O', any surplusage draining back into the crank case.

From the foregoing description it will be 65 readily apparent that while very few parts are employed for carrying the lubricant

to the points desired, nevertheless such parts will allow the lubricant to be properly distributed.

While the preferred form of the invention has been illustrated and described, it is not 70 desired to limit the protection to the particular structure illustrated.

What we claim as our invention is:—

1. In a lubricating system for engines, the combination of an engine casing, said 75 casing have a plurality of spaced partitions, crank shaft bearings carried by said partitions, bearings in said partitions for a second shaft, a conduit extending longitudinally of the crank case, said partitions having conduits therein leading from the longitudinal conduit to the bearings of one of said shafts and having conduits therein leading from the last-mentioned bearings to the bearings of the other shaft. 80

2. In a lubricating system for engines, the combination of an engine casing, a bearing in said casing for a shaft, a conduit extending longitudinally of said casing, means 90 for feeding lubricant to said conduit, a conduit connecting the longitudinal conduit with said bearing, drive mechanism at one end of the crank case, and means for lubricating said drive mechanism from said longitudinal conduit. 95

3. In a lubricating system for engines, the combination of an engine casing, bearings in said casing for a shaft, a conduit extending longitudinally of said casing, means for feeding lubricant to said conduit, 100 accessory drive mechanism at one end of the casing, and means for lubricating said drive mechanism from said conduit and conduits leading from said longitudinal conduit to said bearing. 105

4. In a lubricating system for engines, the combination of an engine casing, bearings in said casing for a shaft, a conduit extending longitudinally of said casing, means for feeding lubricant to said conduit, accessory drive mechanism at one end of the casing, means for lubricating said 110 drive mechanism from said conduit, conduits leading from said longitudinal conduit to said bearing, bearings in said casing for a second shaft, and conduits connecting the first-mentioned bearings with the last-mentioned bearings. 115

5. In a lubricating system for engines, the combination of an engine casing, bearings in said casing for a shaft, a conduit extending longitudinally of the casing, conduits connecting said bearings with the longitudinal conduit, a supply chamber 120 mounting the casing, a connection between said supply chamber and said longitudinal conduit, and means for supplying lubricant to said chamber. 125

6. In a lubricating system for engines, the combination of an engine casing, bear- 130

ings in said engine casing, a conduit, connections between said bearings and said conduit, a valve rod chamber, and a lubricant supply chamber connected with said first-
5 mentioned chamber and with said conduit.

7. In a lubricating system for engines, the combination of an engine casing, a casing having a partition, a bearing in said partition, a second bearing in said partition, 10 a lubricant supply conduit, a conduit formed in said partition leading from the supply conduit to the first-mentioned bearing, a second conduit formed in the partition leading from one bearing to the other, and a bushing for the first-mentioned bearing having openings therein registering respectively with the conduits formed in the partition, said bushing being provided with a channel connecting the openings. 15

8. In a lubricating system for engines, the combination with an engine casing, of a valve rod chamber, valve rods immersed in a lubricant in said chamber, means for supplying lubricant to said chamber, and means 20 for maintaining a constant level of the lubricant in said chamber.

9. In a lubricating system for engines,

the combination with an engine casing, of parallel shafts extending longitudinally of said casing, bearings for said shafts, conduits connecting the bearings of one of said shafts with those of the other, a conduit extending parallel to said shafts, means for supplying lubricant to said conduit, supplying lubricant to the bearings of one of 30 said shafts, mechanism for actuating one of said shafts from the other, and means for lubricating said mechanism from said conduit.

10. In a lubricating system, the combination with a bearing, of a bushing in said bearing having two substantially radial openings and provided with a channel connecting said openings, said bearings having conduits permanently registering with said 40 openings respectively for conducting lubricant to and from the bushing.

In testimony whereof we affix our signatures in presence of two witnesses.

FRANK E. WATTS.
